UNITED STATES PATENT OFFICE.

ALLAN S. BARROWS, OF LOS ANGELES, CALIFORNIA, ASSIGNOR TO THE YOUNGSTOWN STEEL DOOR COMPANY, OF CLEVELAND, OHIO, A CORPORATION OF OHIO.

DOOR.

Application filed January 8, 1923. Serial No. 611,243.

This invention relates to improvements in car doors.

One object of the invention is to provide a car door of the double outside sliding type and more particularly such a door for box cars used in the transporting of automobiles, furniture and other articles of large size.

A specific object of the invention is to provide a double door composed of sheet metal, and wherein maximum strength against thrust in every direction for a given weight is obtained.

Another specific object of the invention is to provide a double door wherein the secondary or auxiliary door has the front edge thereof so constructed and braced, in combination with inexpensive fixtures used therewith, as to provide unusual strength against lateral thrusts.

Another specific object of the invention is to provide novel and efficient means, particularly adaptable to steel sheet metal construction, for locking the secondary or auxiliary door in its so-called closed position.

Other objects of the invention will more clearly appear from the description and claims hereinafter following.

In the drawings forming a part of this specification, Figure 1 is a side elevational view of a portion of a car showing my improvements in connection therewith, parts being broken away in order to better accommodate the figure on the sheet. Figure 2 is an enlarged broken horizontal sectional view corresponding to the section line 2-2 of Figure 1. Figure 3 is an enlarged vertical sectional view corresponding to the section line 3-3 of Figure 1. Figure 4 is an inside elevation view of the front edge of the secondary or auxiliary door and parts immediately associated therewith, the door being shown in closed position. Figure 5 is a detail perspective of certain fixtures employed at the front edge of the secondary door. Figure 6 is an enlarged horizontal sectional view corresponding to the section line 6-6 of Figure 1. Figures 7 and 8 are detail perspectives of two different wedges employed on the doors. Figure 9 is an enlarged vertical section view taken lengthwise of one of the wedge pockets, hereinafter referred to. Figures 10 and 11 are elevational and vertical sectional views, respectively, of the locking mechanism for the auxiliary door. Figure 12 is a view similar to Figure 3, illustrating

another embodiment of my improvements. Figure 13 is an outside elevational view of the front lower corner of the door illustrated in Figure 12. And Figure 14 is a vertical sectional view corresponding to the section line 14-14 of Figure 13.

Referring first to the construction illustrated in Figures 1 to 11 inclusive, 20 indicates the usual side plate of a box car, 21 the side facia board, 22 the door lintel, 23 the floor boards, 24 the threshold plate, 25 a car side sill, 26 a supporting block for extended floor boards and 27 one of the door posts or jams, the one at the rear edge of the auxiliary door, it being understood that there will be a similar post at the opposite side of the large door opening.

In the arrangement shown, two sliding outside doors are employed, one which may be termed the main door and designated A and the other a somewhat narrower door which may be termed the secondary or auxiliary door, which is indicated by the reference character B. In the form shown in Figures 1 to 11, the doors are of the top hung type, each preferably being provided with a pair of roller carrying brackets 28-28, each bracket having a roller 29 which rides upon a Z-bar track 30, the brackets being so formed that they clear the outermost flange of the track and the door having its upper edge extending inside of the outermost track flange, so as to thereby prevent the door from moving outwardly with respect to the track. The main door A is composed of sheet metal throughout, the same preferably being formed with vertical and horizontal corrugations and multiple-ply edges, as described in my Patent No. 1,315,537. The secondary door B is also formed of sheet metal of a construction similar, in greater part, to the main door A, but differing in certain essential features, particularly at its front edge, as hereinafter described. To prevent the lower edges of the doors being swung or pushed outwardly, I provide a series of guide brackets 31, 32 and 33, each of which is provided with an upstanding flange 34 (see Figure 6) spaced from the side wall of the car and having a double beveled or cam surface 35. The rear lower corner of the door B preferably has secured thereto a double-wedge casting of the form best indicated in Figure 7 and referenced 36 so that the same will wedge against the respective guide brackets carried by the car 110

body. At the front lower corners of each of the doors A and B, that is, the two meeting corners as illustrated in Figure 1, each door is preferably provided with a single wedge bracket 37 of the type indicated in Figure 8. When the two doors A and B are closed, as shown in Figure 1, the respective brackets 37 will engage behind the guide bracket 33 and hence prevent the corners of the doors being forced outwardly or sprung open.

The door B, as heretofore explained, is comprised principally of sheet metal, the same preferably being made with a plurality of sheet metal panels suitably united along their meeting edges and forming the main sheet of the door, the latter being then corrugated so as to provide a rear vertical edge corrugation 38, a lower horizontally extending corrugation 39, a partial vertical corrugation 40 at the front edge of the door, and a series of horizontally extending corrugations 41 within the three-edge corrugations referred to, the corrugations 41 merging at their ends with the vertical corrugations 38 and 40. At the bottom of the door B, a plate 42 is riveted or otherwise rigidly secured to the main sheet, said plate 42 bridging the corrugation 39 as shown in Figure 3, and providing a double-ply lower edge. Similarly another strip 43 is employed at the rear edge of the door B on the inner side of the main sheet, the strip 43 bridging the vertical corrugation 38 and riveted to the main sheet on opposite sides of the said corrugation 38, said strip 43 being preferably extended at its rear edge and bent to hook-shape as indicated at 44, so as to engage over the projecting edge 45 of a wear plate 46 applied to the exposed faces of the post 27. In this manner, a spark and weather seal is obtained for the rear edge of the door B.

At the front edge of the door B, a special construction of great strength is employed. The same comprises the extended flange 40^a of the partial corrugation 40, made by the main sheet of the door, a second strip 47 and a section 48 of angle bar, as best shown in Figure 2. The angle bar 48 has an outer relatively narrow flange 49 extending parallel to the side wall of the car and to which is riveted or otherwise rigidly secured, the extension 40^a. The angle section 48 has an elongated leg 50 extended transversely of the car and to which one edge of the strip 47 is riveted or otherwise rigidly secured, as indicated at 51, it being observed that the other edge of the strip 47 is secured to the main sheet of the door at a point inwardly of the corrugation 40, as indicated at 52 and that the strip 47 is extended angularly inwardly from the main plane of the door. As best shown in Figures 3 and 4, the flange 49 of the angle section 48 extends for the full height of the door B, but the leg 50 terminates a short distance below the lintel and a short distance above the threshold. The lower horizontal

strip 42 and the upper corresponding strip 142, which bridges the top horizontal edge corrugation 139, are extended, as indicated at 53 in Figure 2, and thence bent at right angles, as indicated at 54 and riveted to the angle section 48.

With the construction described, it will be observed that I provide what may be termed a tubular edge at the front edge of the door B, said tubular edge being of substantially triangular horizontal section and with a projecting or overhanging marginal flange, consisting of two plies of metal 40^a and 49. This construction is especially adapted to resist bending from thrusts exerted transversely outwardly from the interior of the car, to resist bending from thrusts imparted parallel to the side wall of the car and brace the member 48 against rotation about its longitudinal axis, and also to resist bending or thrusts exerted inwardly against the door. It will be noted also that the double-ply edge 40^a-49 overhangs the front edge of the main door A and is thereby adapted to provide a weather or spark seal at the meeting edges of the two doors.

The elongated leg 50 of the angle section 48 provides a suitable support for a heavy wood nailing block 55, which may be bolted to the angle section, the inner face of the nailing block 55 being in line with the inner face of the post 27. Where the auxiliary door B is not required and when it may be left for a considerable time in its closed position, the door B may be locked in such closed position and boards nailed to the post 27 and the nailing block 55 to continue the inner-sheathing 56 of the car.

To prevent the front edge of the door B from being sprung outwardly, I employ the following fixtures. Partially countersunk within the lintel and partially countersunk within the threshold and anchored by bolts 57-57, are wedged pocket castings designated generally by the reference character C. Each wedge pocket casting C, as best shown in Figures 3, 4, 5 and 9, has a vertically extending loop-shaped flange 58 with a tapered entrance, each loop being opened toward the post 27. Cooperable with the loop-wedging flanges 58 are heavy lugs 59 formed integral with brackets 60-60 secured to the top and bottom, respectively, of the angle section 48. With this construction, the front edge of the door B is properly guided as the door is moved to its closed position and, when the lugs 59 are properly wedged within the flanges 58, outward movement or springing of the front edge of the door B is prevented.

To lock the door B in its closed position, I employ the following means, as best illustrated in Figures 2, 10 and 11. Extending horizontally through the post 27 is a long arm 61 of a U-shaped bolt, the short arm 62 thereof being extended back partially into the post 130

27 and leaving the loop proper 63 of the bolt spaced away from the face of the post. On the lower or elongated arm 61 of the U-bolt, is pivoted a lock lever 64 having an offset handle 65 and an arcuate projection 66 of T cross-section. The projection 66 is adapted to swing within a correspondingly T-slotted casting 67, mounted within one of the horizontal corrugations 41 of the door 10 B so as to lie totally outside of the inner main plane of the door, as best illustrated in Figure 11. When the lever 64 is in the position shown in Figure 11, it is evident that the door B will be prevented from movement in an opening direction and also, when the lever 64 is moved from engagement with the cooperating member 67 of the door, the latter may be moved to its open position without any interference. To hold the lever 64 in its locked position, the lever is provided with a short arm above its pivotal point, to which is pivotally connected a hook latch 69 adapted to take over the short arm 62 of the U-bolt, as shown best in Figure 11. The lever 64 is released by disengaging the latch 69 from the U-bolt as will be understood by those skilled in the art.

Referring next to the construction illustrated in Figures 12, 13 and 14. The structural features of the doors are substantially the same as those illustrated in the figures previously described, except for the specific differences hereinafter described. In the arrangement shown in Figures 12 to 14, the door is of the so-called "bottom hung" type with the supporting rollers 129 riding upon a channel-shaped track 130 supported from suitable brackets secured to the side sill. The top edge of the door is guided beneath a longitudinally extending, approximately Z-sectioned strip 70, secured to the outer depending flange 71 of a Z-bar 72. Along the lower edge of the door, is provided a Z-bar 73 having depending flange 74 engaging behind the channel track 130 so as to prevent the bottom edge of the door from being sprung outwardly.

To adequately support each of the rollers 129 on a sheet metal door of the preferred type, I employ the following arrangement. At each corner where a roller is provided, a portion 75 of the main sheet of the door, which would ordinarily form a continuation of the lower horizontal edge corrugation 76 is extended vertically in line with the outermost plane of the door and spaced from the re-inforcing strip 77, which is secured to the bottom edge of the door, as best shown in Figure 14. To brace the vertical portion 75 of the sheet metal, I secure beneath it, an extra strip 78 having flanges 79 at each end secured to the strip 77 and a vertical longitudinally extending section 80, immediately beneath the plate portion 75. The extra plate 78 and portion 75 are in turn braced or rein-

forced by an outside rectangular plate 81 riveted thereto. A journal 82 having reduced ends is supported by the three plates 81, 75 and 80 at one of its ends and by the strip 77 and Z-bar 73 at its other end, said journal 82 having the roller 129 rotatably mounted thereon. With this arrangement, I provide the necessary strength against crushing or collapse of the parts from vertical loads or thrusts and also against lateral thrusts while maintaining the weight at a minimum.

I have herein shown and described what I now consider the preferred manner of carrying out the invention, but the same is merely illustrative and I contemplate all changes and modifications that come within the scope of the claims appended hereto.

I claim:

1. As an article of manufacture, a door comprised of sheet metal provided with bracing indentations, said door including portions diverging outwardly, and a member having a portion arranged substantially normal to the main plane of said door and connecting with the spaced end portions of said diverging portions to provide one edge thereof of approximately triangular tubular cross-section.

2. As an article of manufacture, a door having the main portion thereof comprised of sheet metal and provided along one vertical edge with a corrugation; a sheet metal strip secured to the main body of the door inwardly of said corrugation and diverging therefrom, and a third member secured to the free edge of said strip and to the free edge of the sheet metal forming the corrugation.

3. In a car, the combination with a sliding door, having a fabricated metal front edge including portions diverging outwardly and connected to provide a construction of approximately triangular horizontal cross section; lugs rigidly secured to said free edge of said door and projecting upwardly and downwardly therefrom respectively; cooperating fixed guide pockets on the lintel and threshold of the car door opening adapted to limit the forward movement of said lugs; and means on the car body adjacent the rear edge of the said door for locking the same in closed position.

4. In a member having a door opening with door posts at the sides thereof, the combination with a metal sliding door having a horizontal corrugation therein extended outwardly from the inner plane of the door; of a shouldered locking block secured to the door within said corrugation adjacent one edge of the door; and a pivoted shouldered locking lever mounted on the door post adjacent said edge of the door when the latter is in closed position, said lever cooperating with said lock to hold the door in closed position.

5. In a car, the combination with a main sliding door; of an auxiliary sheet metal sliding door having a horizontally extending cor-

rugation therein disposed outwardly of the inner plane of the door; of a shouldered locking block secured to the door within said corrugation adjacent the rear edge of said auxiliary door; and a shouldered locking lever pivotally mounted on the door post adjacent said rear edge of the auxiliary door when the latter is in closed position, said lever cooperating with said block and adapted to hold the auxiliary door in closed position.

6. As an article of manufacture, a slidable sheet metal door having a horizontal bottom edge corrugation formed therein; of a bottom supporting roller for said door; and means for mounting said roller on the door comprising, a reinforcing strip secured to the main metal sheet of the door in line with said horizontal corrugation, and a second reinforcing plate having an angularly offset portion included therein and flanged at its ends and interposed between said strip and main metal sheet and secured to both, said roller having journaled support in said strip reinforcing plate and main sheet.

7. As an article of manufacture, a sheet metal door having a bottom horizontal edge corrugation formed therein integral with the main sheet of the door; of a reinforcing strip secured to the inner side of said main sheet in line with said horizontal corrugation; a reinforcing plate having flanged ends and an intermediate angularly offset section, said plate being interposed between said strip and the main sheet of the door in line with said corrugation; a reinforcing bar secured along the inner side of the door at the bottom edge thereof; an outside reinforcing plate secured to the main sheet of the door opposite said first named reinforcing plate; and a roller mounted between said angularly offset section of the first named reinforcing plate and the strip and having journaled support in said bar, strip, reinforcing plates and main sheet.

8. As an article of manufacture, a door having a main portion thereof comprised of sheet metal and provided along one edge thereof with a corrugation extending lengthwise of the edge and disposed to one side of the main plane of the sheet, a reinforcing strip secured to the main sheet and extended to the opposite side of the main plane, and a third metal member secured to the edges of said strip and the free edge of the main sheet beyond the side corrugation.

9. In a member having a door opening defined in part by door posts, the combination with a slidable metal door having a corrugation therein parallel to the line of movement of the door, the corrugation being extended outwardly from the inner plane of the door; a locking member secured to the inner face of the door post at the rear edge of said door when the latter is in closed position, said member having a portion thereof movable to a position within said corrugation of the

door; and cooperating means within said corrugation adapted to coact with said member to lock the door in closed position.

10. In a sliding car door of the character described, the combination with a main body portion; of means associated with the forward edge portion of said door to provide an abutting member adapted to cooperate with a second door, said abutting member being rigidly secured to said first door and having means associated therewith and extending transversely of said door and inwardly beyond the inner face of said door; a nailing block; and means for securing said nailing block to said transversely extending means, said securing means being arranged inwardly of the door and extending substantially parallel with the main plane thereof.

11. In a sliding door of the character described, the combination with a main body portion adapted to cooperate with a second sliding door; of means in the form of a member rigidly secured to said first door and adapted to provide a movable element against which said second door is adapted to abut, said member having a part extending inwardly beyond the inner face of said door substantially at right angles thereto and providing means to which a nailing post may be secured.

12. In a sliding door of the character described, the combination with a main body portion; of means associated with one edge portion of said door to provide a member against which a second door is adapted to abut, said means being rigidly secured to said first door and including a section extending inwardly beyond the inner face of said door a suitable distance substantially at right angles to the main plane of the door, said section being adapted to have a nailing block secured thereto; and a bracing element extending between said section and the main body portion of said door.

13. In a car door, the combination with a main body member having an angular portion adjacent one edge of said door and extending to one side of the main plane of the door; a strip secured to said main body member inwardly of said angular portion; and a section extending substantially at right angles to the main plane of the main body portion and inwardly beyond the inner face thereof, said section being connected to said strip and main body member at a point in spaced relation with respect to the connection of said strip with said main body member; a nailing block; and securing means for attaching said block to said inwardly extending section, said securing means being disposed inwardly of the main plane of said body member and extending in a direction substantially parallel to said plane.

14. In a car door, the combination with a main body member having an edge portion

- made up of a plurality of plies of material extending toward the edge of said door, said plies having portions thereof in spaced relation to provide a reinforcement; and means connected to said plies and extending inwardly beyond the inner face of said door to provide means to which a nailing block may be secured. 15. In a sliding door of the character described, the combination with a main door portion; of a door frame; means adjacent the forward edge of said door adapted to provide an abutment for a second door, said means including a member extending inwardly beyond the inner face of said door and substantially at right angles to the main plane thereof; a wedge bracket secured to the frame of said door; and an element mounted on said inwardly extending member and adapted to engage said wedging bracket upon movement of said door to its operative position. 16. In a sliding door of the character described, the combination with a main door portion; of a door frame; means adjacent the forward edge of said door adapted to provide an abutment for a second door, said means including a member extending inwardly beyond the inner face of said door; a wedge bracket secured to the door frame; an element mounted on said inwardly extending member and adapted to engage said wedging bracket upon movement of said door to its operative position, and latch means automatically engaging said door for preventing rearward movement thereof after said door reaches its operative position. 17. In a railway car, the combination with a sliding door and a frame therefor; of means associated with the forward edge of said door adapted to provide an abutment for a second door, said means including a member projecting inwardly beyond the inner face of said door and transversely with respect thereto; a wedge bracket secured to said frame on the inner side of said door; an element mounted on said inwardly extending member and adapted to cooperate with said wedge bracket; a second wedge means mounted on the car structure at the outer side of said door; and means mounted on said door and adapted to cooperate with said second wedge means when said door is moved to operative position. 18. In a railway car, the combination with a door frame; of supporting means secured to the car structure adjacent the bottom of said door frame; of a sliding door provided with a bottom edge construction including a vertically arranged member; a reinforcing section of angular formation having one portion lying flatwise against the lower edge portion of said vertical member, and having another portion disposed at right angles to said first portion and extending in a direction co- inciding with the bottom edge of said vertical member; and inter-engaging means upon said supporting means and said angular reinforcing section for preventing outward swinging of the bottom of said door with reference to said supporting means. 19. In a door of the character described, comprising a main body sheet, having an angular portion formed therein adjacent one edge thereof, said angular portion being provided with an extension forming the extremity of said main body sheet; an angular member having one angular portion disposed substantially parallel to the main plane of said main body sheet, and another angular portion extending at right angles inwardly toward the main plane of said body sheet; and means secured to said main body sheet inwardly of the angular portion, said means extending in spaced relation with the reference to said angular portion and the extension thereon, and being connected to the angular portion of said reinforcing section extending toward said main body sheet. 20. As an article of manufacture, a car door comprising a main body portion and having means connected to said body portion at one edge thereof, said means being disposed at substantially right angles to the main plane of the door; a member extending at right angles to the main plane of said door, said portion being rigidly affixed to said means; and means engaging said member and the body portion of said door for bracing said member against rotation about its longitudinal axis. 21. In a car, the combination with a main sliding door; of an auxiliary sliding door having a metallic body portion; of a member secured to the forward edge of said metallic body portion and extending substantially at right angles to the main plane of said body portion and adapted to co-operate with the adjacent edge of said main sliding door; and means associated with said auxiliary door for bracing said member against rotation about its longitudinal axis. 22. As an article of manufacture, a door adapted for railway cars, said door including a main body portion and provided at the forward edge thereof with a vertically extending metallic element having sections arranged at substantially right angles to said main body portion, one of said sections extending inwardly of the main plane of the door and to which is adapted to be secured a nailing block. 23. As an article of manufacture, a door adapted for railway cars, said door including a main body portion and provided at the forward edge thereof with a vertically extending metallic element having sections arranged at substantially right angles to said main body portion, one of said sections extending inwardly of the main plane of the door and to

which is adapted to be secured a nailing block, and means for bracing the inwardly extended section.

24. In a car, the combination with main and auxiliary oppositely sliding doors arranged to have their front edges meet when the doors are in closed position, said auxiliary door including the main body portion provided at the forward edge thereof with a vertically extending metallic element having sections arranged at substantially right angles to said main body portion, one of said sections extending inwardly of the main plane of the door to which is adapted to be secured a nailing block, and a portion on said auxiliary door arranged to over-lap the forward edge of the main door to thereby provide a weather seal when the two doors are closed.

25. As an article of manufacture, a door adapted for railway cars, said door including a main body portion and provided at the forward edge thereof with a vertically extending metallic element having sections arranged at substantially right angles to the plane of the main body portion, one of said sections extending inwardly of the main plane of the door, to which one end portion of a grain closure may be attached when the latter is applied in position on the inner side of said door.

26. In a sliding door of the character described, the combination with a door frame; of a door having a main body portion; means adjacent the forward edge of said door, including a member extending inwardly beyond the inner face of said door portion and substantially at right angles to the main plane thereof; a bracket secured to the frame of said door; and an element mounted on said inwardly extending member and adapted to engage said bracket upon movement of said door to its operative position, said bracket having means providing a stop for limiting the forward movement of said door.

27. As an article of manufacture, a car door comprising a main body portion of sheet metal, having an off-set adjacent one edge; and means forming with said off-set a tubular construction along the edge of the door, said means including a flanged portion extending outwardly at an angle to the main plane of the body portion and forwardly to provide a weather sealing flange.

28. As an article of manufacture, a sheet metal door having an off-set adjacent its edge, and having a reinforcing member secured to said edge to which a nailing block is rigidly affixed, said reinforcing member being pro-

vided with a flange which extends forwardly of said off-set in spaced and overhanging relation with reference to said nailing block.

29. In a construction of the character described, comprising an auxiliary sliding door and a main sliding door, said auxiliary door having means at its forward edge to provide a groove for the reception of the forward edge of the main sliding door, said main sliding door having a reduced edge portion disposable in said recess, and having a transversely widened body portion adapted to abut with the forward edge of the means providing the recess of the auxiliary door.

30. A door comprising a main sheet metal body portion defining the general plane of the door, and metal edge portions diverging to opposite sides of said general plane of the main body portion; and a separate metal member extending along said edge of the door and rigidly secured to the spaced longitudinal free edges of said diverging portions whereby the said member is braced by said diverging portions against thrust toward the main portion of the door and against lateral twist.

31. A slideable metal car door comprised mainly of sheet metal and having a lower horizontally extending edge in the general plane of the door; and a member reinforcing said lower edge, said member having a vertical section, a horizontal section and a depending vertical section offset from said first named vertical section, said first named vertical section being secured to said lower edge of the door and said depending vertical section extending below said lower edge of the door proper and adapted to cooperate with door-guiding means on the car to prevent outward swing of the door.

32. An auxiliary slideable door for house cars of the double door type, said auxiliary door having a main portion and provided, along its vertical front edge, with a metal reinforcing member extending in a general direction transverse to the plane of the door and provided along its outer edge with a forwardly projecting flange section whereby said member reinforces the forward edge of the auxiliary door, is adapted to serve as an abutment for the forward edge of the other door and is flanged to overlap said other door and thereby provide weather protection at the meeting edges of the doors.

In witness that I claim the foregoing I have hereunto subscribed my name this 21st day of December, 1922.

ALLAN S. BARROWS.
